PROTECTOR FOR WINDOWS

Arnold Zukor, New York, N. Y.

Application September 14, 1938, Serial No. 229,826

5 Claims. (Cl. 177—314)

This invention relates to new and useful improvements in a protector for windows.

The invention has for an object to provide a plurality of vertical telescopic members adapted to be extended across a window opening, and to be locked in the extended position for assisting in protecting a home or other establishment.

The invention proposes the association of an alarm with the telescopic members arranged to be set into operation when an intruder grips the telescopic members and shakes them in an effort to break in.

Still further the invention contemplates associating the alarm system with the sashes of the window so that the alarm will be set into operation when an intruder moves the sashes. It is pointed out that should an intruder cut out the glass of the sashes without moving them he will still have to pass the obstacle of the telescopic bars before he can enter the room.

Still further the invention contemplates to so construct the device that it can be applied to a window having sliding sashes or to a window of the French type.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an inside elevational view of a window provided with protection device constructed according to this invention.

Fig. 2 is a view similar to Fig. 1 but showing the device with the telescopic members in operative positions.

Fig. 3 is a horizontal sectional view on the line 3—3 of Fig. 2.

Fig. 4 is a fragmentary vertical sectional view on the line 4—4 of Fig. 3.

Fig. 5 is a fragmentary enlarged vertical sectional view on the line 5—5 of Fig. 2.

Fig. 6 is a horizontal sectional view on the line 6—6 of Fig. 1.

Fig. 7 is a fragmentary transverse sectional view on the line 7—7 of Fig. 9.

Fig. 8 is a fragmentary enlarged sectional view on the line 8—8 of Fig. 7.

Fig. 9 is a horizontal sectional view on the line 9—9 of Fig. 7.

Fig. 10 is a fragmentary sectional view taken on the line 10—10 of Fig. 7.

Fig. 11 is a fragmentary sectional view on the line 11—11 of Fig. 9.

Fig. 12 is a schematic wiring diagram of the device.

The protector for windows according to this invention is used in combination with a window frame 10 and sashes 11. The sashes 11 are mounted within an auxiliary frame which is slidably supported in the frame 10 so as to be slidably vertical. Springs 13 are interposed between the top and bottom arms of the frame 10 and the top and bottom arms of the frame 12. These springs 13 serve to hold the auxiliary frame 12 in a central normal position.

The arrangement is such that when the sashes 11 are moved up or down the auxiliary frame 12 will be similarly moved, but through a much larger distance. It is the frictional engagement between the sashes 11 and the auxiliary frame 12 which will cause the auxiliary frame to be moved. The auxiliary frame 12 will return to its normal position as soon as one ceases to move the sashes. The sashes 11 are counter-weighted in the usual manner.

There are sash cords 14 connected with the sides of the sashes which engage over pulleys 15 mounted through openings 16 in the side arms of the auxiliary frame 12. The arrangement is such that the sashes 11 will maintain various raised and lowered positions into which they are placed. A bracket 17 is mounted across the top of the frame 10. The bracket 17 has several lugs 18 engaged by fastening elements 19 which engage the frame 10 and serve to hold the bracket in position. A plurality of vertical flexible telescopic members 20 are mounted upon the bracket 17 and are adapted to extend downwards across the said window.

Each of the flexible telescopic members 20 consist of a plurality of telescopic tubes 20^a, 20^b, 20^c, etc. These tubes may be moved one within the other to assume a collapsed condition as illustrated in Fig. 1. Or these tubes may be extended to extend downwards across the window as shown in Fig. 2. Each of the tube sections of each telescopic member is provided with cooperating grooves and pegs. A peg 21 is mounted on each section and engages a groove 22 on an adjacent section for limiting the sliding of the sections. Therefore, while it is possible to extend the sections the engagement of the pegs with the grooves prevents complete disengagement of the sections from each other.

A bar 24 is extended across the bottom of the window. A means is provided for supporting said

bar to swing slightly forwards and rearwards. This means includes a telescopic member consisting of tubular sections 25 and 26. The bottom section 26 is mounted upon a flange 27 which is attached to the bottom of a casing 28 adapted to house certain parts hereinafter more fully described. The top telescopic section 25 is connected with the bar 24. A latch is provided for holding the telescopic sections 25 and 26 in extended positions. This latch includes bolts 29 urged into extended positions by a spring 30. These bolts and the spring are housed in a casing 31 mounted transversely through the telescopic tube 25.

15 The bolts 29 are adapted to extend over the edges of the top opening in the telescopic tube 26. The top opening in the tube 26 is of a larger diameter than the outside diameter of the tube 25. Several rubber or other resilient washers 32 20 and 33 engage the adjacent walls of tubes 25 and 26, the portions within the tube 26, to flexibly hold these tubes relative to each other. The washer 32 is supported by several rings 34 fixed upon the inner wall of the tube 26. The washer 25 32 engages the outside wall of the tube 25. Several rings 35 are mounted on the tube 25 and support the washer 33 which in turn engages the inside wall of the tube 26. It is therefore possible to shake the bar 24 slightly forwards and rearwards.

30 A means is provided for locking the extended ends of the telescopic members 20 to the said bar 24. This means includes, for each bar, a pair of pintles 36 pivotally supported at their lower ends upon a thin flange 37 extended from the bottom of the lowermost telescopic section of the telescopic member 20. A pintle 38 is used for pivotally supporting the pintles 36. Projections 39 from the flange 37 limit the extension of the pintles 36. A lock plate 40 is slidably supported beneath the bar 24 by several rivets 41 which are fixedly mounted on the bar 24 and which engage through longitudinally elongated slots 42 (see Fig. 9) formed in the lock plate 40. The lock plate 40 is formed with a longitudinal slot 43 which is the same width as the width of the flanges 37.

45 At several points along the length of this slot 43 there are branch slots 44. These branch slots 50 are arranged at locations so that in a certain position of the lock plate 40 they will be aligned with the bolts 36. Then the telescopic members 20 are free from the bar 24. The lock plate 40 is urged into a locking position by a spring 45. 55 One end of the spring 45 is attached upon a lug 46 projecting from the underside of the bar 24. The other end of the spring 45 engages the end 43' of the slot 43. The spring 45 therefore serves to urge the lock plate 40 towards the left, in relation to Fig. 9. A handle 47 (see Fig. 1) is mounted on the underside of the lock plate 40 and is adapted to be manually gripped to move the lock 40 towards the right to a position in which the branch slots 40 align with the bolts 36. This 65 latter position is one in which the telescopic members 20 are now free from the bar 24.

70 Because of the length of the telescopic members 20, in the fully extended positions of the sections thereof, there will be sufficient flexibility to permit the bar 24 to move slightly forwards and rearwards when an intruder grips the telescopic members 20 and shakes them in an attempt to break in.

75 An alarm system is associated with the bar 24. This alarm system includes four contacts 50

arranged two along one side and two along the other side of the bar 24. These contacts 50 are located in the vicinity of the end portions of the bar 24. At these end portions the bar 24 is provided with projecting hook portions 24^a. These hook portions 24^a are adapted to engage and hook on to the extended edges of the contacts 50. The contacts 50 are resiliently supported. Each contact is mounted in a bracket 51 supported upon an inner wall of the casing 28. Each bracket 51 is formed with a slot extending from end to end through which the contact 50 is inserted. Each bracket 51 is formed with several openings 52 in its bottom face through which springs 53 are inserted. Plugs 54 are then used 15 to close the openings 52. These springs 53 serve to urge the contacts 50 into a raised position. The hooks 24 are constructed to have front bevelled edges which normally urge the contacts 50 downwards until the hook portions catch the 20 top edges of the contacts. Then the bar 24 is latched in this position.

The contacts 50 are connected together to move up and down as a unit. There is a bar 55 connecting together the front two contacts 50. 25 The front and rear contacts 50 are connected together at the sides by bars 56. It is therefore possible to release the bar 24 by manually moving the bar 55 downwards. Thus all four of the contacts 50 are moved downwards and the bar 30 24 is released. The bar 24 is formed with the hook portions 24^a at the four sides of its ends. Consequently, the bar 24 may be locked by the contacts 50 in a forward or rearward position.

35 The casing 28 is provided with a door 57 having a lock 58 by which it is normally locked. It is when this door 57 is opened that one may move the contacts 50 and the handle 47 for the purpose previously outlined. The casing 28 is arranged immediately below the window sill 59 40 of the window. The window sill 59 is formed with a pair of covers 60 which are hingedly supported at their outer ends by hinges 61. At their inner ends the covers 60 are provided with handles 62 by which they may be gripped to be 45 opened.

50 The bar 24 is adapted to be moved forwards and rearwards by the auxiliary frame 12. At the bottom a vertical rack 63 projects from the auxiliary frame 12. This rack meshes with a pinion 64 which is fixed on a shaft 65 rotatively supported. Another pinion 66 is fixed on this shaft. This latter pinion is engaged by a rack 67 which is mounted horizontally upon one side of the bar 24. When the sashes 11 are moved, which indirectly cause the moving of the auxiliary frame 12, either up or down, the motion will be transmitted to move the bar 24 either forwards or rearwards so that the bar engages either the front or rear pair of contacts 50.

55 A means is provided for holding the sections of each of the telescopic members 20 in collapsed position. This means consists of a bar 70 which is slidably supported in a horizontal position in brackets 71 mounted upon the window frame 10. 65 The bar 70 is provided with a plurality of fingers 72^a, 72^b, etc., of varying lengths. These fingers selectively engage beneath the lowermost sections of the telescopic members 20. A pin 73 is mounted upon the bar 70 and is engaged by the forked 70 end 74^a of a lever 75 which is pivotally mounted intermediate of its ends by a pintle 76. The lever 75 may be pivoted to move the bar 70. The fingers 72^a, 72^b, etc. are so located in respect to the telescopic members 20 so that as the bar 70 75

moves, the finger 10^a will move free from its telescopic members 20 to drop the sections thereof. Then as the bar 10 continues to be moved the finger 72^b will move free of its telescopic member 20 to drop the sections thereof. In this manner each of the telescopic members 20 will be released in succession one at a time. There is sufficient space between the fingers 12^a, 72^b, etc., so that the fingers do not interfere with the extension of any of the telescopic members 20. The telescopic members 20 may also be released and lowered in any other suitable manner.

The alarm system includes a small alarm 77^a intended to be located within the premises, and a large alarm 77^b intended for exterior use. This large alarm is arranged within a tubular casing 77 extending to the exterior of the house or establishment, through the wall 78 thereof. A shield 79 is extended across the tubular member 77 and is supported in position by several braces 80. The arrangement is such that the sound from the alarm 77^b may pass through the space beneath the shield 79 to the exterior. The contacts 50 are connected with a lead 81 which includes in series the alarm 77^a, a hand switch 82, and one terminal of an electric supply 83. The other terminal of the electric supply is connected by a lead 84 to the bar 24. The alarm 77^b is included in a circuit 85 shunted across the leads 81 and 82. The circuit 85 is arranged to be controlled by a hand switch 86.

The operation of the device is as follows:

Normally, the device is as shown in Fig. 1. In this condition the window sashes are unobstructed and the window sill is closed by the covers 60. To place the device into operative condition it is first necessary that the covers 60 be lifted to the positions shown in Fig. 2. Then the bar 24 is lifted from its lowered position, shown in Fig. 1, to that shown in Fig. 2. When the bar 24 is lifted up the telescopic tubes 25 and 26 will be extended. They will be held in extended position by the bolts 29.

Then the lever 15 is moved to drop the telescopic members 20 one at a time. The lower ends of these members are forced into the slot 43 of the lock plate 40. The bolts 36 of each of these members will open up beneath the plate and so the members will become locked to the bar 24. The uppermost tubes of the telescopic members 20, that is the tubes 20^a, are locked to the bracket 17 by punchings 20' or any other similar means. Because of the pins 21 and the grooves 22 it will not be possible to turn the sections of the telescopic members 20 relative to each other. Therefore, the bolts 36 will maintain locked positions transversely across the slot 43. The switch 82 or the switch 86 is then closed, or both switches closed, depending upon whether it is desired that one alarm operate, or that the alarms operate simultaneously.

Should an intruder desire to break in and move the sashes 11 the alarm will be set into operation for the reason that motion of the sashes 11 will be transmitted to the auxiliary frame 12, and then by reason of the rack 63 the pinions 64 and 66 and the rack 67 to the bar 24. The bar 24 will then move forwards or rearwards and the hooks 24^a lock on to the front pair or the rear pair of contacts 50. This closes the alarm circuit and the alarm will start ringing.

In the event that an intruder does not move the sashes 11, but cuts out a portion of the window glass, then he will encounter the vertical telescopic members 20. These members will stop his

entrance. Should he shake these members in an attempt to break them down the bar 24 will be moved either forwards or rearwards and the hook portions 24^a will engage the contacts 50 and again the circuit through the alarm will be closed.

The burglar alarm may be set to an inoperative position by a person capable of opening the lock 58 and the door 57. This person may now reach the bar 55 and pull down on the bar 10 to move the contacts 50 downwards. This releases the hooks 24^a and the bar 24 will return to a central inoperative position. The various telescopic members 20 may be disconnected from the bar 24 by gripping the handle 47 and pushing the lock plate 40 laterally so that the branch openings 44 align with the bolts 36. The bolts 36 may now pass through these openings and the telescopic members are free.

It is to be understood that this arrangement may be installed in finished buildings or built in any new building and used with the usual sliding window sash or any swing type window, by connecting the locking handle of the window to the telescopic members 20, in any suitable manner.

It is also to be understood that the telescopic members may be either round, square, or any other shape in cross section, with or without any guiding grooves 22 and ornamented to harmonize with the surroundings. The telescopic tubes in the telescopic member 20 are of suitable length and in the closed position causes no obstructions and are hidden from sight.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In combination with a window frame, a bracket mounted on the top of said frame, a plurality of vertical flexible telescopic members mounted on said bracket and adapted to extend across said frame, a bar extended across the bottom of said frame, means for supporting said bar to swing slightly forwards and rearwards, means for locking the extended ends of said telescopic members to said bar, electric contacts to the front and rear of said bar, means for latching said bar to said contacts, an alarm, and a circuit for sounding said alarm when the bar and contact are connected.

2. In combination with a window frame, a bracket mounted on the top of said frame, a plurality of vertical flexible telescopic members mounted on said bracket and adapted to extend across said frame, a bar extended across the bottom of said frame, means for supporting said bar to swing slightly forwards and rearwards, means for locking the extended ends of said telescopic members to said bar, electric contacts to the front and rear of said bar, means for latching said bar to said contacts, an alarm, a circuit for sounding said alarm when the bar and contact are connected, and means for making it possible to lower the bar to an inoperative position.

3. In combination with a window frame, a bracket mounted on the top of said frame, a plurality of vertical flexible telescopic members mounted on said bracket and adapted to extend

across said frame, a bar extended across the bottom of said frame, means for supporting said bar to swing slightly forwards and rearwards, means for locking the extended ends of said telescopic members to said bar, electric contacts to the front and rear of said bar, means for latching said bar to said contacts, an alarm, a circuit for sounding said alarm when the bar and contact are connected, and means for dropping said telescopic members in succession.

4. In combination with a window frame, a bracket mounted on the top of said frame, a plurality of vertical flexible telescopic members mounted on said bracket and adapted to be extended vertically of said frame, a bar slidably mounted across said frame in close proximity to said bracket, a plurality of fingers, one for each of said members, mounted on said bar and engaging the bottom end of said members in their contracted positions for holding the same raised, and means for moving said bar in one direction to disengage said fingers from said members so that said members may be extended, each of said fingers being of a different length and extended in a direction opposed to the direction in which said bar is adapted to be moved for successionally freeing said members when said bar is moved, said fingers being L-shaped and having one of their arms attached to said bar and the other of their arms engageable beneath said members and said arms which are adapted to engage said members being of different lengths.

5. In combination with a window frame, a bracket mounted on the top of said frame, a plurality of vertical flexible telescopic members mounted on said bracket and adapted to be extended vertically of said frame, a bar slidably mounted across said frame in close proximity to said bracket, a plurality of fingers, one for each of said members, mounted on said bar and engaging the bottom end of said members in their contracted positions for holding the same raised, and means for moving said bar in one direction to disengage said fingers from said members so that said members may be extended, each of said fingers being of a different length and extended in a direction opposed to the direction in which said bar is adapted to be moved for successionally freeing said members when said bar is moved.

5. In combination with a window frame, a bracket mounted on the top of said frame, a plurality of vertical flexible telescopic members mounted on said bracket and adapted to be extended vertically of said frame, a bar slidably mounted across said frame in close proximity to said bracket, a plurality of fingers, one for each of said members, mounted on said bar and engaging the bottom end of said members in their contracted positions for holding the same raised, and means for moving said bar in one direction to disengage said fingers from said members so that said members may be extended, each of said fingers being of a different length and extended in a direction opposed to the direction in which said bar is adapted to be moved for successionally freeing said members when said bar is moved, said fingers being L-shaped and having one of their arms attached to said bar and the other of their arms engageable beneath said members and said arms which are adapted to engage said members being of different lengths.

ARNOLD ZUKOR.
